SAFETY RAZOR

Robert John, New York, N. Y.

Application June 27, 1932, Serial No. 619,571

19 Claims. (Cl. 30—50)

This invention relates to safety razors and particularly to blades used therein of the type where a thin flexible steel provided with two cutting edges is employed.

5 An object of the invention is to provide a blade adapted to fit any conventional razor which may be employed either singly or in pairs at the option of the user.

The invention represents an improvement upon 10 the broad idea of providing a plurality of safety razor blades to present a plurality of cutting edges during each stroke of the razor. The advantages and theory underlying the mode of operation of this broad idea is clearly set forth in 15 United States Patent No. 1,024,509, dated April 30, 1912.

In the patent aforesaid and others existing in 20 the domestic and foreign arts, however, the pairs of blades employed separator plates or spaces which I have discovered as highly objectionable, and the present invention contemplates, among other things, a structure wherein no separator plates are employed between the clamping portions of the razor parts.

25 A further object of the invention is to provide means for separating the cutting edges of the pairs of blades so that varying cutting angles are produced.

A further object of the invention is to provide 30 means for securing accurate registration of the pairs of blades so that the mere act of tightening them in the holder insures that the cutting edges are parallel and that each of the blades is exactly centered with respect to the other.

35 Other and subordinate characteristics of my invention will be apparent to those skilled in the art from a reading of the following specification in conjunction with the drawing attached hereto and forming a part hereof in which:

40 Fig. 1 is a side elevation of the razor with a pair of blades positioned therein before the clamp has been drawn down in a manner to flex the blades;

Fig. 2 is a similar view showing the razor in operative condition;

45 Fig. 3 is a top view of one of the blades constituting my invention;

Fig. 4 is a sectional view thereof; and

Fig. 5 is a view showing in dotted lines the disposition of a cooperating blade when pairs of 50 blades are employed.

Now, referring more specifically to the invention, 1 indicates a razor of any desired form having a guard 3 provided with a channel 4 and a clamping portion 5. The numeral 6 represents 55 the usual curved upper clamp having suitable

pins 7 for registering the clamp with the guard. The structure thus far described corresponds to a conventional razor now in popular use.

The numeral 8 is a razor blade constituting my invention having oppositely disposed cutting edges 9 and 10 and provided with side wings 11 and 12 which project laterally from the ends of the clamp and guard, as shown in the dotted line 13. This blade may have a longitudinal recess 14. Adjacent one of the cutting edges 10 only of the blade is a narrow elevated structure running lengthwise of the blade as indicated by reference numeral 15. This elevated structure may consist of a narrow strip of material such as celluloid or metal foil, cemented to the 15 blade, or it may be formed by punching a depression upon the opposite side of the blade before hardening and grinding, or it may be a single straight line elevation. Again it may consist of a broken line comprising elevated dots in a 20 straight row. The height of the elevation is governed by the amount of spacing desired between the two cutting edges; I find that an elevation of from five to ten thousandths of an inch gives a satisfactory separation between the two 25 cutting edges for average use although this may be materially increased or decreased for special purposes.

When it is desired to use my blade in single form in the conventional way, it is merely placed 30 in the usual holder with the projection disposed downwardly, whereupon the cutting edges assume the exact position which they would assume in the case of the regular blade minus the projection. If, however, it is desired, to secure the 35 advantages of my invention, to use the blades in pairs, all that is necessary to do is to place the blades together in such a position that the projection of one blade is near one edge of the pair while the projection of the other blade is near the 40 other edge of the pair. The pair is then simply inserted in the regular holder which, when tightened, tends to force the cutting edges of the lower blade downwardly, apart from those of the upper blade. The projections, being close to the 45 cutting edges, are spaced outwardly of the under-clamping surface, with the result that, when used singly or in pairs, the standard clamping device of the razor lies inside the projection or projections, whereby the clamping operation is in nowise 50 interfered with. This is clearly shown in Fig. 2 of the drawing. When using the blades in pairs it is imperative that the cutting edges be perfectly aligned in parallel; otherwise, the advantages of the double cutting edge are nullified and 55

the cutting characteristics of the razor are disadvantageously altered. In order to provide exact, automatic registration of my blades when used in pairs, I provide four punched-up projections on the wing portions of each blade which project laterally from the holder and are thus outside the clamping mechanism. These projections may conveniently take the form of conical bosses of about ten thousandths of an inch 5 in height, projecting on one side and indented on the other, two of said bosses nearest one cutting edge of the blade being disposed upwardly, as indicated at 16, while the other two nearest the other cutting edge are disposed downwardly, 10 as indicated at 17. Said bosses, being outside of the clamping mechanism of the razor holder, perform no function and present no interference when the blade is used singly. However, when the blades are used in pairs and their projection 15 sides or wings are brought face to face, it will be seen that the upward conical formation of one blade fits into the downward conical formation of the other blade, as indicated in Fig. 5 at 18 and 19 respectively, and vice versa, and because 20 of the conical structure, the mere act of tightening the clamp centers and aligns the blades with 25 relation to each other.

From an examination of the drawing, it will be seen that my new blade, when used in pairs, presents certain advantages over ordinary blades used with separators, to-wit: (1) The upper blade is closer to the guard than is possible when separators are used since the space between the clamps is represented by two razor blades, whereas, when a separator is used, the space between the clamps is represented by the thickness of the 30 blades plus the thickness of the separator. Throwing the upper blade outward even by the space of a thin separator may place it in a position where it is so far out of its alignment with its original design that the smoothness of its cutting function may be interfered with. By 35 eliminating the separator, the present invention minimizes this difficulty and, in fact, brings the upper blade to a position frequently employed when close, smooth shaving is desired; and (2) The lower blade, being bent downward outside the clamping device, presents a slightly different cutting angle than the upper blade instead of 40 possessing the same angle, which it gives when a separator is used, said separate angles of the two cutting edges providing smoother and more effective shaving at a single stroke than when the cutting edges are at the same angle.

50 55 What I claim is:

1. A safety razor comprising a clamping mechanism, a pair of blades secured therein in face to face relationship, and means for separating the adjacent cutting edges of said blades when the 50 clamping mechanism is actuated to clamp the blades so as to impart variant cutting angles to said blades.

2. A safety razor of the class described including clamping mechanism, a pair of blades secured 65 within said clamping mechanism in face to face relationship, and means for automatically separating the adjacent cutting edges of said blades during the tightening adjustment of said clamping mechanism.

70 75 3. A safety razor of the class described comprising a clamping mechanism, a pair of blades secured thereby and means provided on said blades for separating the adjacent cutting edges upon tightening adjustment of the clamping mechanism.

4. A safety razor mechanism of the class described comprising a guard and a clamp, said guard being provided with a longitudinal channel, a pair of thin flexible safety razor blades disposed between the guard and clamp, means 5 disposed between the blades outside the clamping area of the guard for separating the edges of the blades.

5. A safety razor of the class described comprising a guard and an upper clamp, said guard 10 being provided with a longitudinal channel, a pair of safety razor blades positioned in face to face relationship disposed between the guard and clamp with portions of the blades contacting, means for separating the cutting edges of 15 the blades, said means being adapted, upon the adjustment of the clamp, to cause the cutting edge of the lower blade to project downwardly into said channel whereby to provide cutting edges of said pair of blades of different angles. 20

6. A safety razor of the character described comprising a guard and a clamp, means for adjusting the relative positions of the guard and clamp, said guard having a longitudinally extending channel, a pair of blades disposed between the guard and clamp with portions of the blades contacting, the under surface of said clamp being uniformly curved, means for separating the cutting edges of said pair of blades, said means being disposed above said channel 30 portion of the guard whereby, upon adjustment of the clamp, relative to the guard the lower blade is caused to be flexed downwardly to produce a cutting angle greater than that of the upper blade disposed directly beneath said clamp. 35

7. A safety razor of the class described comprising a clamping mechanism, a pair of blades disposed within said clamping mechanism and interfitting means carried by the blades for 40 maintaining their edges in parallel position upon actuation of the clamping mechanism.

8. A safety razor of the character described comprising a clamping mechanism, a pair of 45 flexible blades mounted within said clamping mechanism, means for adjusting said clamping mechanism to flex the blades, and interfitting means carried by said blades to maintain their edges in parallel position when the adjusting mechanism is actuated. 50

9. A safety razor of the character described comprising clamping mechanism, a pair of blades disposed in contact with each other within said clamping mechanism and adapted to be flexed 55 thereby, interacting means between the pair of blades for preventing relative movement thereof during said flexing movement.

10. A safety razor of the character described comprising clamping mechanism, a pair of blades 60 disposed in contacting face to face relationship, within said clamping mechanism, an intervening separator having means for separating the cutting edges only of said blades and interacting means between the pair of blades for preventing relative movement of the blades when the clamping mechanism is actuated. 65

11. A safety razor of the character described comprising a razor blade having opposite longitudinally disposed cutting edges, an elevated portion provided closely adjacent one of the cutting edges only of said blade, a similar complementary razor blade superimposed directly thereon in such a position that the respective elevated portions of the blades cause separation of the opposite cutting edges thereof, and interfitting 70 75 75

means between the blades for causing automatic registration thereof when adjusted within the clamping mechanism of a razor.

12. A safety razor blade of the character described made of thin flexible metal, an elevated structure disposed longitudinally and in close proximity to one of the cutting edges only of said blade, laterally projecting portions provided by the blade normally disposed beyond the clamping area of the clamping mechanism of a razor, said laterally projecting portions having oppositely disposed bosses, said blade being adapted to be employed with a complementary blade having similar formations whereby the elevated portion of one blade is caused to separate the cutting edges along one side of the pair of blades and the elevated portion provided by the other blade adapted to separate the cutting edges along the adjacent sides of the blade, the oppositely disposed bosses of one blade being adapted to interfit with the similar bosses of the other to secure registration of the blades when positioned within the clamping mechanism.

13. A safety razor of the character described comprising a guard and a clamp, a pair of contacting razor blades disposed between said guard and clamp, the opposing surfaces of said guard and clamp being formed to cause the two blades to assume a curved position when clamped and means to maintain the blade positioned adjacent said guard in a position of greater curvature than the outer blade.

14. A safety razor of the class described comprising a clamping mechanism, a pair of flexible blades positioned therein, and means provided on said blades for flexing the blades and causing the edges thereof to assume variant angles upon actuation of the clamping mechanism.

15. A safety razor comprising a clamping mechanism, a pair of blades secured therein in face to face relationship, and means provided on said blades for imparting variant angles to the cutting edges of said blades when the clamping mechanism is tightened.

45 16. A safety razor comprising a clamping

mechanism, a pair of blades secured therein in face to face relationship, means carried by said blades for imparting variant angles to the cutting edges of said blades when the clamping mechanism is actuated, and separate interacting means carried by said blades for maintaining the cutting edges in parallel position.

17. A safety razor of the class described comprising a clamping mechanism, a pair of blades secured thereby, each blade being provided with means for separating the adjacent cutting edges upon the tightening adjustment of said clamping mechanism.

18. A safety razor blade having a cutting edge along each side, an elevated structure disposed longitudinally and in close proximity to one cutting edge only, said blade being adapted to be employed in a clamping mechanism with a complementary blade having a similar formation whereby, when the clamping mechanism is tightened, the elevated portion of one blade is caused to separate the cutting edges along one side of the pair of blades and the elevated portion provided on the other blade is caused to separate the cutting edges along the opposite side of the blades.

19. A safety razor blade having a cutting edge along each side, an elevated structure disposed longitudinally and in close proximity to one cutting edge only, and bosses provided on the blade, said blade being adapted to be employed in a clamping mechanism with a complementary blade having similar formations whereby, when the clamping mechanism is tightened, the elevated portion of one blade causes the cutting edges along one side of the pair of blades to assume variant angles and the elevated portion provided on the other blade causes the cutting edges along the opposite side of the blades to assume variant angles, the bosses of one blade being adapted to interfit with the similar bosses of the other blade to maintain the adjacent cutting edges of the blades in parallel position.

ROBERT JOHN. 45
